UNITED STATES PATENT OFFICE.

HENRY A. WISE WOOD, OF NEW YORK, N. Y., ASSIGNOR TO WOOD NEWSPAPER MACHINERY CORPORATION, OF NEW YORK, N. Y., A CORPORATION OF VIRGINIA.

KNIFE BOX FOR CUTTING CYLINDERS.

Application filed October 3, 1923. Serial No. 666,364.

This invention relates to a knife box for a cutting cylinder co-operating with a folding cylinder for cutting a web of paper passing between them.

5 The principal object of the invention is to provide an improved knife box, removable as a whole, for supporting the cutting knife so that the cheek blocks which surround it will be capable of yielding to permit the 10 knife to act. The invention also involves the provision of wide staggered springs back of the blade and independent thereof and individually adjustable.

Reference is to be had to the accompanying drawings, in which

Fig. 1 is a fragmentary transverse sectional view of a folding and cutting cylinder embodying this invention and showing the knife cutting the web;

20 Fig. 2 is a similar view of the parts of the cutting cylinder when not in cutting position;

Fig. 3 is an elevation of the cutting cylinder broken away and showing it with the 25 knife box removed at one end;

Fig. 4 is a side view of a part of the knife box;

Figs. 5 and 6 are enlarged views of two forms of cutters that can be used in connection with this invention; and

Fig. 7 is an enlarged section of the cutting blade on the line 7—7 of Fig. 5.

I have shown the invention as used with the ordinary folding cylinder 10 having a 35 block 11 therein supporting a yielding pad 12 of rubber or the like for the cutting knife to act against.

I have shown the invention as used with an ordinary cutting cylinder 13 co-operating 40 with the folding cylinder as indicated for drawing the web W between them. In this cutting cylinder, I provide a radial recess 14 in which is located the knife box 15—16. The knife box consists of two parts as indicated, both of them removably fixed in the recess in the cylinder, the two being connected together by cross studs 18 extending through the two. Through both of these 45 parts extend and are slidably located rods 20 which are fitted into and positively connected with two plates 21 in a recess 22 in the knife box. In this recess is located a pair of cheek blocks 23 having a longitudinal space

between them for receiving the cutting blade 24. The cheek blocks have slots 32 for the 55 studs 18.

The cutting blade is made up of sections 60 adjustably fixed to one of the parts of the knife box by bolts 17 in slots 19. They are located in fixed position projecting beyond the circumference of the cylinder at all times.

In a recess 25 behind a fixed plate 26 at the bottom of the knife box are a series of 65 springs 27. Each bears on two plates 28 in the recess at its ends. An adjusting screw 29 is located in a screw threaded passage in the cylinder for engaging each bottom plate 28 and adjusting the compression of the 70 spring 27. The springs are wide and in staggered position.

These springs 27 tend to force the cheek 75 blocks 23 out to the position shown in Fig. 2 at all times. When the cylinders rotate in contact with each other into the position

shown in Fig. 1, the cheek block is forced 80 back against the springs by the folding cylinder and the knife blade 24 is thus left in exposed position to cut across the web and sever it.

The knife blade can be formed with ordinary saw teeth as shown in Fig. 5 or with saw teeth having one edge transverse to the longitudinal direction of the knife and the other edge 31, which constitutes really the 85 cutting edge, at a more acute angle as shown in Fig. 6. The blade is plane on one side, as shown in Fig. 7, to ensure a straight clean cut.

In this manner I secure an automatic acting knife which is firmly fixed in the cutting cylinder and therefore does not have to move and yet I can have all the advantage of a reciprocable knife. Also I can adjust the compression of the springs 27 in accordance with the wear of the parts and the reduction of the resiliency of the spring after wear. The leading end of the web is not tucked in and no corner formed on the web.

Although I have illustrated and described 100 only a single form of the invention, I am aware of the fact that modifications can be made therein by any person skilled in the art without departing from the scope of the invention as expressed in the claims. Therefore I do not wish to be limited to all the 105

details of construction herein shown and described, but what I do claim is:—

1. In a web cutting machine, the combination with a cutting cylinder, of a cutting knife mounted in stationary position therein, and a pair of cheek blocks surrounding the knife, of springs for normally forcing the cheek blocks outwardly, and means for adjusting the compression of the springs arranged to be operated from the side of the cylinder opposite to that of the cheek blocks.

2. In a knife box for a web cutting device, the combination with a cutting cylinder and a pair of members fixed in position therein and having a recess between them, of a pair of cheek blocks reciprocably mounted in said recess, rods connected with the cheek blocks and extending through the knife box, springs behind the knife box for pressing on the rods and normally forcing the cheek blocks out, and a blade fixed in position on the knife box, said cheek blocks having a space therebetween for the blade.

3. The combination with a cutting cylinder for a web folding machine, of a cutting blade fixed therein, radially reciprocable cheek blocks and a set of springs for projecting the cheek blocks which are so positioned that those bearing upon one cheek block bear a staggered relation to those bearing upon the other cheek block.

4. The combination with a cutting cylinder for a web folding machine, of a cutting

blade fixed therein, a reciprocable cheek block on each side of the blade, a set of springs for normally projecting the cheek blocks, and means for individually adjusting said springs from the outside of the cutting cylinder at a point at a distance circumferentially from the cheek blocks.

5. The combination with a cutting cylinder of a web folding machine, of a saw toothed cutting blade smooth on one side and having teeth perpendicular on one edge to the length of the blade and slanting on the other edge so as to come to a sharp perforating point and beveled on the slanting edge.

6. In a web cutting machine, the combination with a folding cylinder and a cutting cylinder of a cutting knife mounted in stationary position on the cutting cylinder and a pair of cheek blocks located on each side of the knife, a set of springs for yieldingly forcing the cheek blocks outwardly, the cheek blocks being so positioned that those springs bearing upon one cheek block bear a staggered relation to those bearing upon the other cheek blocks, and means for adjusting the tension of said springs which may be operated without the removal of the said cheek blocks.

In testimony whereof I have hereunto affixed my signature.

HENRY A. WISE WOOD.
